UNITED STATES PATENT OFFICE.

LEO ROSENMAN, OF BROOKLYN, NEW YORK, ASSIGNOR TO R. K. M. MFG. COMPANY, A. CORPORATION OF NEW JERSEY.

GARMENT-FASTENER HOLDER.

1,171,982.

Specification of Letters Patent. Patented Feb. 15, 1916.

Application filed August 12, 1914. Serial No. 856,397.

To all whom it may concern:

Be it known that I, LEO ROSENMAN, a citizen of the United States, residing at 882 Lafayette street, Brooklyn, New York, have 5 invented certain new and useful Improvements in Garment-Fastener Holders, fully described and represented in the following specification and the accompanying drawings, forming a part of the same.

10 The present invention has reference, generally, to improvements in fastening hooks and eyes, and other similar fastenings to garments; and, this invention relates, more particularly, to improvements in "flies" for 15 garments, comprising a plurality of fabric-members, to be hereinafter respectively termed, the fabric-base and the covering-strip which are suitably connected by sewing, the covering-strip having a folded-over 20 portion or other suitable marginal edge, said covering-strip being sewed fast along the said folded-over portion or marginal edge to the said fabric-base, but at suitable intervals such stitching along said folded-over 25 portion or marginal edge being omitted, providing what may be termed "gaps", and forming marginal openings of substantially the width of the shank-portions of hooks and eyes, but of less width than the bases 30 or main body-portions of hooks and eyes, or similar fastenings, in which pocket-like portions the fasteners will be held against 35 tilting or other insecure fastening relation.

The present invention has for its principal object to provide "flies" for garments, 40 consisting of a fabric-base and a covering-strip, which may be in the form of a compound strip to be sewed fast to the garment, or may be in the nature of a covering-strip 45 sewed directly to the garment, in which case the latter constitutes the base-fabric, with suitably disposed pocket-like portions for the reception of hooks and eyes, or similar fastenings, and for the retention of such 50 hooks and eyes, or similar fastenings in such pocket-like portions, without any portion or portions of the stitching passing through the bases or main body-portions, or other parts of the fasteners, or by riveting them in position.

The invention has for its further object 55 to provide fastener-holding means, as above stated, along a line back of the bases or main body-portions of the metallic fasteners, as hooks and eyes, or similar fasteners,

with a row of stitches, which may be applied along the rear of the fasteners when the fly or strip is being manufactured, or when the fly is secured by stitching to a garment.

Other objects of the present invention not at this time more particularly enumerated will be clearly understood from the following detailed description of the present invention.

With the various objects of the present invention in view, the said invention consists, primarily, in the novel "fly", and novel means of providing "flies" with pocket-like portions for the reception of hooks and eyes, or other similar fasteners, without stitching the fasteners *per se* to the "fly"; and the invention consists, furthermore in the novel arrangements and combination of the several devices and parts, all of which will be more fully described in the following specification, and then finally embodied in the clauses of the claim which are appended to and which form an essential part of the same.

Any subject-matter of the invention herein shown, but not claimed, is set forth and claimed in another application for Letters-Patent filed by me subsequent hereto on August 11th, 1915, Serial No. 44,855/15.

The invention is illustrated in the accompanying drawings, in which:—

Figure 1 is a plan view, showing fragmentary portions of the fabric-base and covering-strip stitched thereto in the manner of the present invention in readiness for the fasteners to be slipped in place in the pocket-like receiving portions. Fig. 2 is a similar view of the base-fabric and covering-strip sewed to a section of a garment, with the eyes in position in the pocket-like receiving portions; and Fig. 3 is a similar view of another compound strip sewed to another section of a garment, with the hooks in position in the pocket-like receiving portions. Fig. 4 is a sectional representation, taken on line 4—4 in said Fig. 3, said view being made on an enlarged scale. Fig. 5 is a perspective view of the base-fabric and the covering-strip sewed fast thereto along its marginal edge-portion, the parts being represented in a distorted relation, to illustrate more particularly the intervals of the "gaps" forming the openings of the pocket-like receiving-portions. Fig. 110

6 is a plan view, on an enlarged scale, of one of the eyes employed in said Fig. 2. Fig. 7 is a transverse sectional representation, taken on line 7—7 in said Fig. 3.

5 Similar characters of reference are employed in all of the above described views, to indicate corresponding parts.

Referring now to the several figures of the drawings, the reference-character *a* indicates the covering-strip and *b* the base-fabric, both being of any suitable material, and being connected by means of stitching, in the manner to be presently set forth, to provide a compound strip or "fly." The 10 manner of attaching said covering-strip *a* to the fabric-base *b* is to provide the strip *a* along one of its longitudinal marginal edges with a fold, as *a'*, or other finished edge, and then by means of a suitable sewing machine, or otherwise, sewing along said edge, thereby providing a row of stitching as *c*. At intervals this stitching *c* is made at angles usually at right angles, but not essentially so, to the main line of stitching *c*, in 15 a direction toward the edge *a'*, as at *c'*, thereby providing a tying stitch, and consequently a reinforcement at one end of the gap, the stitching *c'* leaving the edge *a'* and continuing for a short distance and in the 20 same direction along the said base-fabric *b*. Upon this base-fabric *b*, the stitching is then made, as at *c''*, slightly longer than the width of the shanks of the hooks and eyes, said line of stitching *c''*, being substantially 25 parallel to the edge *a'*, of the covering-strip *a*. At the proper point, the stitching is again angularly turned as at *c'*, upon the said base-fabric *b* in a direction toward the fold or edge *a'*, the stitching *c'* continuing 30 for a short distance upon the said fold *a'*, through the covering-strip *a* and the base-fabric *b*, thereby providing another tying stitch, and consequently a reinforcement at the other end of the gap, and then being 35 again angularly turned and continuing in the original direction of the main line of stitching *c* along the marginal edge-portion or fold *a'*, all of which will be clearly evident from an inspection of Fig. 1 of the 40 drawings. As clearly shown in said Fig. 1, the angular lines of stitching *c'* may be doubled upon each other, by sewing back and forth, thus providing what may be termed "tacks," the ends of said "tacks" located above the base-fabric being connected 45 by the stitching *c''*, in the manner shown. In this manner, as will be fully understood, at proper intervals the fold or marginal edge *a'* of the covering-strip *a* is not sewed 50 fast to the base-fabric *b*, thereby forming "gaps" which provide suitable openings *d* of pocket-like receiving spaces between the fastened covering-strip and the base-fabric.

The hooks and eyes are respectively indicated by the reference-characters *e* and *f*,

the base-portions of the hooks *e* being connected with the shank-portions of said hooks by means of the angular members *e'*, as indicated in dotted outline in said Fig. 3 of the drawings, and the base-portions of the eyes *f* being connected with the shank-portions of said eyes by means of the angular members *f'*, as indicated in Figs. 2 and 6 of the drawings.

To insert the hooks *e* or eyes *f* in position, they are inserted between the connected covering-strip *a* and the base-fabric *b*, their shank-portions being passed into and through the respective openings *d* with their base-portions resting directly between the connected covering-strip and base-fabric, and with their angular members *e'* and *f'* resting in contact, between the said base-fabric *b* and the covering-strip *a*, with the stitching *c*, and also against the ends of the stitching *c'*, acting as stops to retain the fasteners in place, and the stitching *c'* serving as reinforcements to prevent gapping or distortion of the openings *d*, and thereby more securely and positively retaining the inserted fasteners against tilting in their operative relations to the said covering-strip *a* and the base-fabric *b*, as will be clearly evident.

While in the foregoing, the arrangement of the hooks and eyes, or other similar fasteners, have been described in connection with the cover-strips and base-fabrics of the "flies," it will be understood, that the "flies" may, if desired, be sold without the fasteners therein so that a person may purchase the empty strips and insert the hooks and eyes of the kinds and forms most suitable.

To prevent displacement of the fasteners, after they have been placed in position, in the manner herein-above stated, the covering-strip *a* and the base-fabric *b*, may be stitched fast to the portion *h* of a garment by the rows of stitching *i*, as clearly indicated in Figs. 2 and 3 of the drawings, or, if desired the rows of stitching *i* may be made merely through the two members of the compound strip, that is through the covering-strip *a* and the base-fabric *b*, each row of stitching passing directly back of and adjacent to the rear marginal edges of the fasteners placed in position, substantially as shown in said Figs. 2 and 3. The said compound strip may be further secured to the garment-portions *h* by rows of stitching, as *j* as clearly illustrated in said Figs. 2 and 3.

From the foregoing description of the present invention, it will be evident, that a simple, neat and well-appearing fly for garments has been provided, and that the maximum portions of the fasteners are covered, except their necessary working ends, so that the danger of rusting and thereby rendering the garment unsightly and unfit for wear,

has been reduced to a minimum, and, the general construction is simplified because of the fact that the fasteners can be easily and quickly inserted in place in the pocket-like receiving portions formed, without the necessity of sewing each fastener independently in position, or by the employment of other means for securing the fasteners in place.

10 Of course, I am aware, that some changes may be made in the general arrangements and combinations of the several devices and parts, as well as in the details of the construction of the said parts, without departing from the scope of the present invention as set forth in the foregoing specification, and as defined in the clauses of the claim which are appended thereto. Hence, I do not limit myself to the exact arrangements 15 and combinations of the devices and parts as described in the said specification.

I claim:—

1. The combination with a base-fabric and covering strip sewed together to provide gaps at intervals at the marginal edge 25 of said covering strip, tying stitches extending toward the said marginal edge of the covering strip and adjacent to said gaps, and fasteners located between the base-fabric and the covering strip and between the said tying-strokes, said tying-strokes lying in close proximity to and extending in the same direction as the shanks of the inserted fasteners, and thereby providing 30 means to prevent movement of the said fasteners laterally between said tying-strokes.

2. A fastener-holding means for garments, comprising a base-fabric and a covering-strip, and a line of stitching through said 40 base-fabric and the covering-strip, said stitching being made near the marginal edge of said covering-strip, said stitching being interrupted at intervals along the said edge, but extending over and beyond said edge 45 and along the exposed portions of the base-fabric in front of each interrupted portion in the edge, all arranged to provide spaced pocket-like receiving portions having openings located beneath said marginal edge.

3. A fastener-holding means for garments, comprising a base-fabric and a covering-strip, and a line of stitching through the base-fabric and the covering-strip, said stitching being made near the marginal edge 50 of said covering-strip, said stitching being interrupted at intervals along the said edge, but extending along the exposed portions of the base-fabric in front of each interrupted portion in the edge, all arranged to provide spaced pocket-like receiving portions having openings located beneath said marginal edge, combined with hooks and eyes arranged in said pocket-like receiving portions, said hooks and eyes having angular 55 members connected with their base-portions,

said angular members forming stops abutting in contact between the said base-fabric and the covering-strip with said stitching, and the said hooks and eyes having shanks extending into and from the openings of 70 said pocket-like receiving portions.

4. A fastening-means for garments, comprising a base-fabric and a covering-strip, and a line of stitching through said base-fabric and the covering-strip, said stitching 75 being made near the marginal edge of said covering-strip, said stitching being interrupted at intervals along the said edge, but extending along the exposed portions of the base-fabric in front of each interrupted 80 portion in the edge, all arranged to provide spaced pocket-like receiving portions having openings located beneath said marginal edge of the fold, combined with hooks and eyes arranged in said pocket-like receiving 85 portions, said hooks and eyes having angular members connected with their base-portions, said angular members forming stops abutting in contact between the said base-fabric and the covering-strip with the said 90 stitching, and the said hooks and eyes having shanks extending into and from the openings of said pocket-like receiving portions, and another row of stitching passing directly back of and adjacent to the rear 95 marginal edges of the positioned hooks and eyes.

5. A compound strip for garments adapted to receive fasteners, comprising a base-fabric and a covering-strip, said covering-strip having a marginal fold, a row of stitching through said base-fabric and the covering-strip, said stitching being made close to and extending along the marginal fold, said stitching being interrupted at 105 intervals along said fold, rows of stitching extending at right angles at said interrupted portions to said first-mentioned row of stitching, said right-angled rows of stitching extending from and beyond the 110 marginal edge of the fold and onto the exposed portions of the base-fabric, and lines of stitching upon said base-fabric connecting the ends of said right-angled rows of stitching, all arranged to provide the compound strip with reinforced spaced pocket-like receiving portions having openings located beneath the marginal edge of the fold. 115

6. A compound strip for garments adapted to receive fasteners, comprising a 120 base-fabric and a covering-strip, said covering-strip having a marginal fold, a row of stitching through said base-fabric and the covering strip, said stitching being made close to and extending along the marginal fold, said stitching being interrupted at 125 intervals along said fold, rows of stitching extending at right angles at said interrupted portions to said first-mentioned row of stitching, said right-angled rows of 128

stitching extending from and beyond the marginal edge of the fold and onto the exposed portions of the base-fabric, and lines of stitching upon said base-fabric connecting the ends of said right-angled rows of stitching, all arranged to provide the compound strip with reinforced spaced pocket-like receiving portions having openings located beneath the marginal edge of the fold, 5 combined with hooks and eyes arranged in said pocket-like receiving portions, said hooks and eyes having angular members connected with their base-portions, said angular members forming stops abutting in 10 contact between the said base-fabric and the fold with said first-mentioned row of stitching and also with the inner ends of said right-angled rows of stitching, and the said hooks and eyes having shanks extending 15 into and from the openings of said pocket-like receiving portions and between said right-angled rows of stitching.

7. A compound strip for garments adapted to receive fasteners, comprising a 20 base-fabric and a covering-strip, said covering-strip having a marginal fold, a row of stitching through said base-fabric and the covering-strip, said stitching being made close to and extending along the marginal 25 fold, said stitching being interrupted at intervals along said fold, rows of stitching extending at right angles at said interrupted portions to said first-mentioned row of stitching, said right-angled rows of

stitching extending from and beyond the 35 marginal edge of the fold and onto the exposed portions of the base-fabric, and lines of stitching upon said base-fabric connecting the ends of said right-angled rows of stitching, all arranged to provide the compound strip with reinforced spaced pocket-like receiving portions having openings located beneath the marginal edge of the fold, 40 combined with hooks and eyes arranged in said pocket-like receiving portions, said hooks and eyes having angular members connected with their base-portions, said angular members forming stops abutting in contact between the said base-fabric and the fold with said first-mentioned row of stitching and also with the inner ends of said right-angled rows of stitching, and the said hooks and eyes having shanks extending 45 into and from the openings of said pocket-like receiving portions and between said right-angled rows of stitching, and another 50 row of stitching in said compound strip, said last-mentioned row of stitching passing directly back of and adjacent to the rear marginal edges of the positioned hooks and eyes. 55

In testimony whereof I have hereunto set my hand in the presence of two subscribing witnesses.

LEO ROSENMAN.
